UNITED STATES PATENT OFFICE.

LOUIS P. VALIQUET, OF NEWARK, NEW JERSEY.

ARTIFICIAL EAR-DRUM.

1,045,917.

Specification of Letters Patent. Patented Dec. 3, 1912.

Application filed March 8, 1909. Serial No. 431,877.

To all whom it may concern:

Be it known that I, LOUIS P. VALIQUET, a citizen of the United States of America, and a resident of Newark, county of Essex, 5 State of New Jersey, have invented certain new and useful Improvements in Artificial Ear-Drums, of which the following is a specification.

My invention relates to artificial aids to 10 hearing, and comprises an apparatus which I call an artificial ear drum and which is designed to improve the hearing of persons partly deaf.

The best form of apparatus at present 15 known to me, embodying my invention, is illustrated in the accompanying sheet of drawings, in which:

Figure 1 is a section through a portion of the head of a human being, showing the 20 hearing organs, and my apparatus in position. Fig. 2 is an end view in detail of a portion of my apparatus, and Figs. 3, 4 and 5 show details in section.

Throughout the drawings, like reference 25 figures indicate like parts.

1 represents the outer portion of the human ear, and 2 the canal leading to the ear drum 3. The little bone called the hammer which presses against the inside of the 30 ear drum is shown at 4, while 5 is the bone called the anvil and 6 the stirrup. These bones are located in the space 7 called the middle ear and in the normal person transfer the vibrations of the ear drum 3 to the 35 internal ear 8, composed of spiral canals and nerve filaments.

Deafness may result from perforation or 40 disease of the ear drum 3, or from other causes which render the transmission of vibrations more difficult, or to diseased conditions of the internal ear which render it less sensitive. My invention helps the patient to hear better in all these cases by magnifying the vibrations which are delivered to the 45 bone 4, called the hammer.

My invention comprises the tube 9 adapted 50 to fit into the ear canal and preferably composed of three telescoping sections 10, 11 and 12. The outer section 10, made of metal or hard rubber, or other resonant material, has a flaring portion 21 in which is mounted a diaphragm 22, preferably made of mica. This diaphragm is usually held in place by the wax or cement 13, and by the 55 outer ring 14. The middle section of tube

11, is made of similar material to the outer section and is usually given the reversed or S-shaped curvature indicated in the drawing, so that, by turning it around, the tube as a whole may fit better into the differently 60 curved passages of the ear canal, in different persons. The inner section 12 is made of thin india rubber and terminates in a small diaphragm 15 which is slanted so as to lie flat against the ear drum opposite where the 65 hammer bone 4 touches the inner side of the ear drum.

16 is a cross piece on the outer flaring portion 21 which serves as a handle for removing the apparatus and as a guard for the 70 outer diaphragm.

In use the outer part or section 10 is cast to fit the ear of the user, an impression in wax being first taken. The sections 11 and 12 are twisted so as to best fit into the ear 75 canal and bring the inner diaphragm in complete contact with the ear drum. In practice the apparatus will more nearly fill the ear canal than is indicated in Fig. 1, the drawing having been made with open 80 spaces for clearness of illustration.

The operation of my invention is as follows: On assembling the parts a body of air is confined in the tube 9 between the two diaphragms 22 and 15. The exterior sound 85 waves of the atmosphere strike the larger diaphragm 22 and give it vibrations of a certain amplitude, say one thousandth of an inch each. If the confined air were an incompressible fluid, it would compel the 90 smaller, inner diaphragm 15 to make vibrations of approximately as many times greater amplitude as diaphragm 22 is larger in area than diaphragm 15. Even though the air is elastic, the structure tends to concentrate or exaggerate the vibrations of the larger outer diaphragm upon the smaller inner one through the action of the confined air, and reproduce them in greater amplitude, and as this diaphragm rests directly 95 upon the hammer bone 4, the effect is pronounced, even if the ear drum 3 is perforated or diseased so as to be unable to perform its normal functions. Furthermore, the outer portion of the tube, being of metal or other resonant material, is sharply vibrated by the sound waves of the atmosphere, and doubtless these vibrations are in part transmitted by molecular vibration through the walls of 100 the inner tube and diaphragm to the ham-

110

inner bone against which the latter rests. Whatever the principle of operation, numerous experiments have shown that in a majority of cases of deafness, the hearing is 5 greatly improved by insertion of the above described apparatus in the patient's ear, if said apparatus is of the proper shape to fit the ear and the canal and lie flat against the ear drum.

10 Having, therefore, described my invention, I claim:

1. In an artificial ear drum the combination of a tube with a flaring outer portion, a diaphragm in said flaring outer portion, and 15 a smaller diaphragm at the inner end of the tube adapted to rest snugly against the ear drum.

2. In an artificial ear drum the combination of a tube with a flaring outer portion, a 20 diaphragm in said flaring outer portion, and a smaller diaphragm at the inner end of the tube adapted to rest snugly against the ear drum, the inner end of the tube and the

small diaphragm being formed of india rubber.

3. In an artificial ear drum the combination of a tube with a flaring outer portion, a diaphragm in said flaring outer portion, and a smaller diaphragm at the inner end of the tube adapted to rest snugly against the ear 30 drum, the inner end of the tube and the small diaphragm being formed of india rubber, and the outer portion of the tube and its flaring end being formed of metal.

4. In an artificial ear drum the combination of a tube of substantially air tight construction adapted to fit into the ear canal, and two diaphragms across said tube, one at each end thereof.

Signed at New York, N. Y. this 6th day 40 of March, 1909.

LOUIS P. VALIQUET.
